UNITED STATES PATENT OFFICE.

THOMAS S. WATSON, OF MILWAUKEE, WISCONSIN.

CONVEYING STRUCTURE.

Application filed September 27, 1920. Serial No. 413,017.

To all whom it may concern:

Be it known that I, THOMAS S. WATSON, a citizen of the United States, and resident of Milwaukee, county of Milwaukee, and 5 State of Wisconsin, have invented new and useful Improvements in Conveying Structures, of which the following is a description, reference being had to the accompanying drawings, which are a part of this specification.

The invention relates to conveying structures.

Conveying structures of the travelling bridge type as usually built depend for 15 traction upon the frictional engagement between the wheels on the trucks of the structure and the rails upon which these wheels travel. This sometimes results in one leg of the structure running ahead of the other 20 so that the structure is thrown out of alignment and is liable to collapse or fall over. Furthermore, with the frictional drive there is no safe and positive method for retarding and stopping the travel of the structure, as the rail clamps usually employed 25 also depend upon a frictional engagement which is insufficient to overcome the momentum of the structure and particularly when the structure is subjected to the high wind 30 pressures frequently encountered. These disadvantages have been overcome by a positive drive for the trucks so that both trucks travel uniformly and can therefore be easily maintained in alignment and so that the stopping 35 of the positive driving means will stop the structure since such driving means acts as a positive stop for the structure.

Another object of the invention is to provide a positive drive for the trucks of the 40 structure driven from a common source of power.

Another object of the invention is to provide a simple and efficient form of driving track for the positive drive mechanism.

45 A further object is to provide suitable track anchoring means.

The invention further consists in the several features hereinafter set forth and more particularly defined by claims at the conclusion hereof.

In the drawings: Fig. 1 is a side elevation of a conveying structure equipped with propelling mechanism embodying the invention; Fig. 2 is an end elevation of the struc-

ture shown in Fig. 1; Fig. 3 is a detail side view of one of the propelling trucks, parts being broken away and parts being shown in section; Fig. 4 is a section taken on the line 4—4 of Fig. 3; Fig. 5 is a view of a driving track; Fig. 6 is a detail view of a track support; Fig. 7 is a detail view of a track plate; Fig. 8 is a sectional view similar to Fig. 4 showing a modified arrangement of the propelling mechanism; Fig. 9 is a view similar to Fig. 3 showing another form of propelling mechanism; Fig. 10 is a section taken on the line 10—10 of Fig. 9.

Referring to the drawings, the illustrated conveying structure comprises a conveying bridge 9, the trucks 10 of which are mounted 70 on wheels running on one or more rails, as hereinafter described.

A motor 13 is mounted on the bridge and through gearing 14 drives a line shaft 15 which carries bevel gears 16 meshing with 75 similar gears 17 on transmission shafts 18 carrying gears 19. A brake 15', either of the mechanical or dynamic type, is used for stopping the rotation of the shaft 15.

Referring to Figs. 3 and 4 of the drawings, illustrating the preferred form of the invention, the gear 19 meshes with a gear 40 on a drive shaft 41 carried in the lower portion of one of the trucks 10 which includes truck frame members 42. Supporting and guiding wheels 43 are mounted on axles 44 journalled in the truck and run on rails 45, one rail being used for each leg of the bridge. A propelling wheel 46 is fixed to the shaft 41 as by a keyed connection. 90

In this instance the driving track is formed of plates 47 and 48 carrying transverse pins 49 spaced at regular intervals along the plates forming the track. The wheel 46 has teeth the advancing sides of 95 which are adapted to engage the pins as said wheel is driven to thereby positively drive each leg of the bridge. The plates 47 are disposed in upright position between the head and base of the rail 45 and secured thereto by clamps 51 which also engage the base of the rail and have a top surface 52 upon which the plates 48 rest. With this construction dirt and dust is excluded from the space 53 between the rail 45 and the plate 100 47 and the plate 48 is elevated above the road-bed so that the pins 49 may be easily kept clean and clear of any foreign matter. 105

The pins 49 may be of one piece or they may have a roller portion engaged by the wheel 46.

The driving track shown in Figs. 5 to 8 inclusive include side frame plates or members 29 supported by angle iron brackets 30, one side of each bracket forming a base and the other side having spaced notches 31 formed therein near the top and upon which the plates are seated. Transversely disposed driving pins 32 are secured to the plates 29 in spaced relation and hold the plates together. These rails are made up in sections. At the central portion of each section a pair of brackets 30 are used and longitudinal movement is prevented by plates 33 riveted to the plates 29 and provided with notches 34 fitting over the upright sides of said brackets. At the ends single brackets 30 are used and permit the expansion and contraction of the rail, the rail sections being joined together by plates 29'. This driving track is shown in Fig. 8 and also a rail 35 for the supporting and guiding wheels 36 for the trucks on the legs of the bridge. The transmission shaft 18 has its gear 19 meshing with a gear 37 on a driven axle 38 upon which the wheel 36 at one end of the truck is loosely mounted and the propelling wheel 39, similar to the wheel 46, is keyed to this axle and engages the pins 32 to move the bridge in the same way as the previously described construction. The wheel 36 at the other end of the truck is not shown but is mounted on its own axle similar to the wheel 43 shown in Fig. 3.

Referring to Figs. 9 and 10 of the drawings, the transmission shaft 18 carries a gear 19 meshing with a gear 20 on a driven axle 40 21 carried in the lower portion of one of the frames 10 which includes the frame members 22. Supporting and guiding wheels 23 are loosely mounted on the axle while a propelling wheel 24 is fixed thereto 45 as by a keyed connection.

The driving track is formed of two channel beams 25 mounted above the road-bed upon ties 26 and carrying transverse pins 27 spaced at regular intervals along 50 the beams forming the track. The wheel 24 has teeth 28 the advancing sides of which are adapted to engage the pins as said wheel rotates to thereby propel the bridge structure along the track. The beams are elevated above the road-bed so that the pins 55 may be easily kept clean and clear of any foreign matter. The beams not only form a part of the track but also form the supports for the wheels 23. As shown, the tops 60 of the beams form a rail head for the wheels 23 but it will be understood that separate rail sections for said wheels may be carried on top of the beams, if desired.

To prevent any liability of tipping or 65 5 railment of the structure, stabilizing hooks

40' are shown in Figs. 8 and 10 connected to the truck and have their ends disposed beneath the rail head with which they may engage if for any reason the structure should start to tip to one side or the other.

In the constructions above described it will be noted that the driving pins are secured in elevated position between the side frame members of the track, thus affording unobstructed passage around the pins so 70 that the track may be kept clean and is self-cleaning, as any material passes down onto the road-bed, and that said pins with their supports form a pin rack engaged by the 75 propelling wheel.

The positive drive for each of the spaced trucks of the conveying structure permits of the ready alinement of the trucks, and where the drive is from a common source of power the trucks will be maintained in alinement. 80 Furthermore, by the use of a positive drive the movement of the conveying structure may be retarded and positively stopped since the application of the brake, or brakes where separate drive for each truck is provided, stops the rotation of the propelling 85 wheels and the pins then engaging said wheels act as positive stops to arrest the movement of the structure.

The weight of the structure is carried on 90 the rails so that the driving pins are relieved of any strain occasioned by this weight.

I desire it to be understood that this invention is not to be limited to any specific 100 form or arrangement of parts except in so far as such limitations are specified in the claims.

What I claim as my invention is:

1. The combination, with a conveying 105 structure having a bridge mounted on spaced trucks, of a motor mounted on the bridge, a line shaft driven by the motor, a transmission shaft on each truck drivingly connected with said line shaft, a propelling 110 wheel carried by each of the trucks and drivingly connected with the transmission shaft on that truck, a pin rack adjacent each truck and engaged by the propelling wheel for that truck, a rail mounted adjacent 115 each truck, and guide and supporting wheels mounted on each truck to run on the rail for that truck.

2. The combination, with a conveying 120 structure having a bridge mounted on spaced trucks, of a motor mounted on the bridge, a line shaft driven by the motor, a transmission shaft on each truck drivingly connected with said line shaft, a propelling 125 wheel carried by each of the trucks and drivingly connected with the transmission shaft on that truck, a pin rack adjacent each truck and engaged by the propelling wheel for that truck, a rail mounted adjacent each truck, guide and supporting wheels mounted 130

on each truck to run on the rail for that truck, and means for stopping the rotation of said line shaft.

3. The combination, with a conveying structure having a bridge mounted on spaced trucks, of driving means mounted on the bridge, transmission shafts on each truck operatively connected with and driven by said driving means, a propelling wheel carried by each of the trucks and drivingly

connected with the transmission shaft on that truck, a pin rack adjacent each truck and engaged by the propelling wheel for that truck, a rail mounted adjacent each truck, and guide and supporting wheels 15 mounted on each truck to run on the rail for that truck.

In testimony whereof, I affix my signature.

THOMAS S. WATSON.
